UNITED STATES PATENT OFFICE.

ADOLPH A. THOMAS, OF NEW YORK, N. Y.

ELECTRIC SOUND REPRODUCER.

Application filed March 15, 1926. Serial No. 94,676.

My invention relates to the art of reproducing sound by electrical means, and its object is to provide a sound reproducer capable of giving a richer, fuller and more nearly natural tone reproduction than is possible to obtain with prior devices. At the present time my new instrument finds special usefulness in telephone receivers of the loudspeaker type, although it is not limited

10 to this particular field.

Briefly stated, the reproducer of my invention embodies two diaphragms actuated out of phase with each other by a predetermined amount, so that the sound waves produced by one diaphragm are like reflected or echoed waves of those produced by the other diaphragm. The combined tonal effect of this double reproduction is like hearing the original sound by the natural process of

20 receiving not only the direct but also the reflected sound waves.

It is my theory that the natural reproduction of sound must take into account not only the direct waves issuing from the source of sound, but also the reflected waves that are always present in sound propagation as we encounter it in ordinary life. True, broadcasting studios are so constructed that all reflection of sound waves is prevented

30 and only direct waves strike the microphones. In my opinion that is all wrong,

for it robs the transmitted sound of its natural richness and quality. That is why prior loudspeakers cannot possibly give a natural reproduction of the original sound: they can reproduce only the direct waves that struck the microphone, thus giving a thin reproduction that lacks body.

Right here is where my invention comes to the rescue. By means of two diaphragms operating out of predetermined phase with each other, I supply the previously lacking reflected or echoed waves which are necessary to impart naturalness to speech or music. Any suitable electromagnetic mechanism may be used to actuate the diaphragms. In the embodiment which I prefer at the present time as the best expression of my idea, I employ a pair of independent coils for controlling the operation of the diaphragms. These coils are connected in separate circuits through which flow electric impulses representing transmitted sound. The impulses in one circuit

in the other circuit, with the result that one of the diaphragms slightly lags behind the other diaphragm in the same way that reflected or echoed sound waves lag behind the direct waves. The amount of phase displacement between the impulses in the two controlling circuits can be regulated for the best acoustic effect in each particular instance.

Since the basic idea of my invention may be practically embodied by means of many different constructions, I do not consider it necessary to show or describe, in all mechanical details, any particular form of instrument. My invention will be fully understood from a description of the diagrammatic views illustrated in the accompanying drawings, in which—

Fig. 1 represents diagrammatically a radio loudspeaker embodying the principle of my invention; and

Fig. 2 shows a slightly modified form.

Referring first to Fig. 1, we have a pair of diaphragms A and B, which are supposed to be properly constructed and mounted. Any practical electromagnetic mechanism may be employed to actuate each diaphragm. By way of example I have indicated a pair of magnetic armatures 1 and 2 pivoted centrally at 3 to vibrate between the pole pieces 4 and 5 of a pair of magnets (not shown). The magnets furnish a normally constant field. Each armature is connected to its associated diaphragm by a link or rod 6. Armatures 1 and 2 extend through fixed coils C' and C², respectively. Coil C' is connected in a circuit 7, which also includes a secondary coil S'. Coil C² is connected in a circuit 8 having a secondary coil S² and a choke coil 9. The secondary coils S' and S² are inductively associated with a primary coil P, these three coils constituting a transformer indicated as a whole by T. The primary coil P is in the plate circuit 10 of a vacuum tube V of usual construction. A battery 12 or other source of normally constant potential supplies the primary coil with a flow of normally steady current, which has no effect on the secondary coils S' and S².

It will be understood that potential variations in the grid circuit 13 of the tube produce amplified current impulses through coil P, and these current impulses may be said to be an electric representation or image of the transmitted sound waves. The cur-

rent fluctuations in coil P induce corresponding impulses in the secondary circuits of coils C' and C². However, the impulses in circuit 8 of coil C² will lag behind the impulses in secondary circuit 7 on account of the retarding effect of choke 9, as will be clear to those familiar with this art. In other words, the impulses in secondary circuits 7 and 8 are dephased with respect to each other, and the amount of this phase displacement (ceteris paribus) depends upon the self-inductance of choke coil 9, which is preferably adjustable as to its inductance value. Since the electric impulses passing through coil C² lag behind those of coil C', the vibrations of diaphragm B will slightly lag behind those of diaphragm A. The amount of this lag is only a fraction of a second and should be just enough to represent the phase difference between direct and reflected waves. This can readily be determined by experiment. When the phase displacement between the induced currents in coils C' and C² is properly adjusted, the combined tone effect of the diaphragms will result in a more natural reproduction than is possible to obtain with a single diaphragm or with several diaphragms reproducing only direct sound waves.

If desired, a condenser 14 may be included in secondary circuit 7 to advance the phase of the induced impulses with respect to those in circuit 8. Condenser 14 may be used in lieu of choke 9 or in addition thereto. Ordinarily, however, one or the other of these dephasing devices will be sufficient.

In the modification of Fig. 2, the secondary circuits 7 and 8 are fed with a normally constant current from batteries 15 and 16, respectively, and each circuit preferably includes a variable resistance 17 to control the normal flow of current. The controlling coils C' and C² are mounted on magnets or soft-iron cores 18, the polar ends of which terminate in operative relation to the diaphragms A and B. These, of course, are of magnetic material in this instance. Otherwise, what has been said about Fig. 1 is fully applicable to Fig. 2 without the necessity of repetition.

The diaphragms should preferably be of identical construction, so that one diaphragm is an echoing likeness (as it were) of the other. Although I have spoken of only two diaphragms, it is clear that each diaphragm may be replaced by two or more diaphragms of different natural frequencies to encompass the entire musical scale. In that case, the diaphragms of each set will operate in unison, but the diaphragms of one set will lag behind the other set, as previously explained for diaphragms A and B.

What I claim as my invention is:

1. A sound reproducer having a pair of diaphragms, electromagnetic mechanism for

operating each diaphragm independently of the other, said mechanism being controlled by electric impulses representing transmitted sound, and means for so controlling said mechanism that said electric impulses cause said diaphragms to vibrate slightly out of unison.

2. A sound reproducer having a pair of diaphragms arranged to be operated independently of each other, an electromagnetic actuating device associated with each diaphragm, each of said devices including a coil, means for connecting said coils independently with a common circuit of electric impulses representing transmitted sound, and means for dephasing the impulses in one coil with respect to the impulses in the other coil, whereby the impulses in said circuit cause vibration of said diaphragms in dephased relation.

3. Sound-reproducing apparatus comprising a primary circuit traversed by electric impulses representing transmitted sound, two independent secondary circuits operatively associated with said primary circuit, means for dephasing the induced current impulses in one of the secondary circuits relatively to the impulses in the other secondary circuit, and an acoustic member controlled by the current impulses in each secondary circuit, so that said members vibrate in dephased relation.

4. Sound-reproducing apparatus comprising a primary circuit traversed by electric impulses representing transmitted sound, two independent secondary circuits operatively associated with said primary circuit, means for dephasing the induced current impulses in one of the secondary circuits relatively to the impulses in the other secondary circuit, an acoustic member controlled by the current impulses in each secondary circuit, so that said members vibrate in dephased relation, and means for regulating the amount of phase displacement between the current impulses in the two secondary circuits.

5. An electric sound reproducer having a pair of diaphragms, means for vibrating said diaphragms in dephased relation, and electric means for regulating the amount of phase displacement between said diaphragms.

6. In apparatus for electrically reproducing sound, the combination of a circuit of variable electric impulses, a pair of substantially identical diaphragms, means controlled by said impulses for simultaneously operating said diaphragms, and means for causing one of said diaphragms to lag slightly behind the other.

7. In the art of electrically reproducing sound, the improvement which consists in operating one diaphragm to represent direct sound waves and simultaneously operating

a second diaphragm in lagging phase relation to the first diaphragm to represent reflected sound waves.

8. In the art of electrically reproducing sound, the method which comprises sending electric impulses through a primary circuit, reproducing said impulses in two secondary circuits, displacing the phases of the induced currents in the secondary circuits relatively to each other a predetermined amount, and causing the dephased impulses to operate a pair of diaphragms.

9. A sound reproducer having a pair of diaphragms arranged to be operated inde-

pendently of each other, an electromagnetic actuating device associated with each diaphragm, each of said devices including a coil, means for connecting said coils independently with a common circuit of electric impulses representing transmitted sound, means for dephasing the impulses in one coil with respect to the impulses in the other coil, whereby the impulses in said circuit cause vibration of said diaphragms in dephased relation, and means for adjusting the amount of phase displacement between the electric impulses in the two coils.

ADOLPH A. THOMAS.
